CLAIM

The ornamental design for a sink and shower drain hair collector, as shown and described.

DESCRIPTION

FIG. 1 is a top perspective view of a sink and shower drain hair collector showing our new design;

FIG. 2 is a bottom perspective view thereof;

FIG. 3 is a front view thereof;

FIG. 4 is a back view thereof;

FIG. 5 is a top view thereof;

FIG. 6 is a bottom view thereof;

FIG. 7 is a left view thereof; and,

FIG. 8 is a right view thereof.

The broken line in the drawing showing holes depict portions of the article that form no part of the claim.

1 Claim, 8 Drawing Sheets
